GEORGE W. HINKLEY, JR., OF DANBURY, AND CLIFFORD J. STAIB, OF BETHEL,
CONNECTICUT.

CAN-OPENER.

1,148,229.

Specification of Letters Patent. Patented July 27, 1915.

Application filed November 2, 1914. Serial No. 869,755.

To all whom it may concern:

Be it known that we, (1) GEORGE W. HINKLEY, Jr., and (2) CLIFFORD J. STAIB, citizens of the United States, residing at (1) 5 Danbury and (2) Bethel, county of Fairfield, State of Connecticut, have invented an Improvement in Can-Openers, of which the following is a specification.

This invention has for its object to provide a strong, durable, safe and relatively inexpensive can opener, adapted for family use and especially adapted for use in restaurants and hotels, and by painters or workers in any art where it is required to 15 open a large number of cans of different sizes, our present invention being adapted to cans of all sizes, within reasonable limits, and being easily and quickly adjusted to hold any can firmly and to cut out the cover 20 or to cut a hole of any desired size therein, leaving a small portion of the cut out part still connected to serve as a hinge, if required.

With these and other objects in view, we 25 have devised the novel can opener which we will now describe, referring to the accompanying drawing forming a part of this specification, and using reference characters to indicate the several parts.

30 Figure 1 is an elevation partly broken away illustrating our novel can opener as in use, and Fig. 2 is a detail sectional view illustrating means for locking the cutter in operative position.

35 10 denotes the body which comprises a lower horizontal arm 11 carrying a screw clamp 11 by which the body may be attached to a table, shelf or any fixed part, an upper horizontal arm 12 and a vertical arm 13.

40 The can to be operated upon is placed upon a carrying plate 14 which may be cast integral with or rigidly secured to a head 15 on the horizontal arm. The head, below the carrying plate, is provided with a hole lying 45 in the horizontal plane in which a right and left threaded screw 16 lies without engagement, the screw being retained centrally in the head by collars 17 which are pinned to the screw and engage opposite ends of the 50 head, thus permitting the screw to be rotated freely but retaining it against endwise movement.

55 18 denotes locking jaws which pass through slots 19 in the carrying plate and extend a sufficient distance above it to grip

opposite sides of the base of a can firmly and are provided at their lower ends with threaded hubs 20 which are engaged respectively by the right and left threads of the screw. A crank 21 is attached to the 60 screw for convenience in operation. Rotation of the screw by means of the crank will move the locking jaws toward or from each other to grip or release the base of a can.

The vertical arm is provided with a longitudinal hole extending from the upper end downward in which a rod 22 is adapted to slide. The rod is shown as provided with a groove 23 which is engaged by the point of a thumb screw 24 in the vertical arm to 70 lock the rod at any required vertical adjustment and also to lock it against rotation. Rod 22 carries at its upper end an arm 25 having at its outer end a vertical hole to receive the shank 26 of a rotating carrying 75 block 27 having a transverse hole through it in which a cutter carrying arm 28 is adapted to slide. The hole and cutter carrying arm are made angular in order to prevent rotation of the arm. The lower end of the 80 shank is reduced and threaded to receive a shank 29 which retains the carrying block and cutter carrying arm in place but permits free rotation of the block in swinging the cutter carrying arm around, as will be more 85 fully explained. The lower end of shank 26 is provided with a prong 30 which is in alinement with the center of the carrying plate and is adapted to pierce the center of a can cover to coöperate with the locking 90 jaws in retaining a can to be operated upon perfectly rigid. At the outer end of the cutter carrying arm is a hole to receive a vertical sheath 31 which is rigidly locked in place by a pin 32 engaging a hole drilled 95 both in the sheath and in the arm.

33 denotes the cutter which is provided with a shank extending through the sheath longitudinally and having at its upper end a hand piece 34 provided in its under side with a recess 35 which is adapted to receive the upper end of the sheath. A spring 36 lying between the upper end of the sheath and the base of the recess normally acts to retain the cutter in a raised position in 100 which the cutter is wholly received within the sheath. Should it be required to lock the cutter in the operative position as in Fig. 2, this may be done by means of a thumb screw 37 in the cutter carrying arm, 110

which passes through the sheath and is adapted to engage the shank of the cutter. The cutter carrying arm is locked at the required adjustment in the carrying block by means of a thumb screw 38 in the block. This adjustment determines the size of the hole cut in a can cover.

The operation is as follows: The implement is locked in place by means of the screw clamp, the can to be operated upon is placed upon the carrying plate and the locking jaws are then adjusted to secure it in place. Rod 22 is then lowered to place the prong in engagement with the center of the can cover, the prong being pressed into the cover sufficiently to hold the upper end of the can perfectly rigid. The parts may be locked in this position if required by tightening up thumb screw 24. The operator then adjusts the cutter carrying arm to cut a hole of the required size in the can cover and locks the arm in position by tightening up thumb screw 38. The operator then presses down upon hand piece 34 and forces the cutter through the can cover. The cutter may be locked in this position by tightening up thumb screw 37 or may simply be held down by pressure upon the hand piece while the operator swings the cutter carrying arm around and cuts out the can cover or a hole of any required size therein. The cut is usually started with the sheath in contact with one side of arm 25, as in Fig. 1, and the cutter carrying arm is swung around until the sheath comes into engagement with the other side of arm 25, leaving the cut out piece still connected to the can. The instant pressure upon the hand piece is relieved the spring will draw the cutter up into the sheath, as in Fig. 1. The rod and arm 25 are then raised to disengage the prong from the can cover and the base of the can is released by rotation of the screw. It will be obvious that the operation of opening cans may be performed very quickly, the operation upon each can requiring but a few seconds.

Having thus described our invention we claim:

1. In an implement of the character described, a suitably supported arm provided

near its end with a substantially vertical opening, a carrying block having a shank rotatable within the opening and provided with a substantially horizontal opening, a cutter carrying arm mounted within the substantially horizontal opening and provided near its end with a substantially vertical opening, a substantially vertical sheath arranged within the substantially vertical opening of the cutter carrying arm and clamped therein, a cutter mounted to reciprocate within the sheath and adapted to extend downwardly therebelow and having a shank extending upwardly beyond the sheath, a hand piece attached to the upper end of the shank of the cutter and provided in its lower portion with a recess receiving the upper end of the sheath, and a coil spring surrounding the upper end of the shank of the cutter and arranged wholly within the recess of the hand piece, substantially as described.

2. In an implement of the character described, the combination with a suitably supported movable cutter carrying arm provided near its end with a substantially vertical opening, a substantially vertical sheath arranged within the substantially vertical opening and clamped therein, a cutter mounted to reciprocate within the sheath and adapted to extend downwardly therebeyond and having a shank extending upwardly beyond the sheath, a hand piece attached to the upper end of the shank of the cutter and provided in its lower portion with a recess receiving the upper end of the sheath, a coil spring surrounding the upper end of the shank of the cutter and arranged wholly within the recess of the hand piece, and a clamping screw engaging the sheath and adapted to engage with the shank of the cutter to lock the cutter in the cutter position, substantially as described.

In testimony whereof we affix our signatures in presence of two witnesses.

GEORGE W. HINKLEY, JR.
CLIFFORD J. STAIB.
